HYDROPLANE OR SIMILAR ARTICLE

Ted Geffner, Elmhurst, N. Y.

Application June 7, 1950, Serial No. 10,393

Term of patent 14 years

(Cl. D71--1)

To all whom it may concern:

Be it known that I, Ted Geffner, a citizen of the United States of America, residing in Elmhurst, county of Queens, and State of New York, have invented a new, original, and ornamental Design for a Hydroplane or Similar Article, of which the following is a specification, reference being had to the accompanying drawing, forming part thereof, wherein,

Figure 1 is a side elevational view of a hydroplane, showing my new design.

Figure 2 is a view similar to Figure 1 showing the hood member in a slightly raised position, and showing the side windows lowered.

Figure 3 is a front elevational view of the hydroplane as shown in Figure 1, and

Figure 4 is a rear elevational view thereof.

I claim:

The ornamental design for a hydroplane or similar article, substantially as shown.

TED GEFFNER.
